UNITED STATES PATENT OFFICE.

AMBROSE LAWRENCE, OF MEDICINE LODGE, KANSAS.

ENSILAGE-PACKER.

1,237,916.

Specification of Letters Patent. Patented Aug. 21, 1917.

Application filed February 26, 1917. Serial No. 151,097.

To all whom it may concern:

Be it known that I, AMBROSE LAWRENCE, a citizen of the United States, and a resident of Medicine Lodge, in the county of Barber and State of Kansas, have invented 5 a new and Improved Ensilage-Packer, of which the following is a full, clear, and exact description.

My invention relates to means to be positioned in a silo and operated to pack ensilage.

Objects of the invention are to provide an efficient packer arranged to travel over the ensilage in a circular path; to provide a 15 packer including packing rollers, one of which is power driven, and coned or tapered to cause the packer to travel circularly; and to provide a power driven packer, the total weight of which, including the weight of 20 the motor, as well as the weight of the workman, will be imposed on the ensilage and the whole caused to travel about a relatively fixed centering post as an axis.

Other objects are to provide for permitting the revoluble packer to bodily slide vertically on the centering post as the silo is filled, and to accommodate itself to the surface irregularities of the ensilage without straining the centering post or the parts 30 of the revolving packer, and without binding on said post.

Further objects of the invention are to provide a centering post to be built up of separate sections as the silo is filled; and to 35 construct the revolving packer in simple form, and yet possessing the requisite strength and durability.

Reference is to be had to the accompanying drawings forming a part of this specification in which similar reference characters indicate corresponding parts in all the views.

Figure 1 is a vertical section of a silo on the line 1—1, Fig. 2, showing my improved 45 packer in side elevation;

Fig. 2 is a plan view of the improved packer, the silo being shown in horizontal section;

Fig. 3 is a transverse vertical section of 50 the packer;

Fig. 4 is an elevation, the view being taken at right angles to Fig. 3.

In carrying out my invention in practice, a centering post 10 is provided adapted to 55 be suitably fixed in the silo. In practice said post is made up of separate sections so that

it may be built up as the silo is filled, the sections being connected in any suitable manner as by a tenon 11 and a mortise 11a. The post is shown fixed at its base 12 on the bottom 13 of a silo 14, which may be of any suitable material. The packer is made with suitable frame work including a platform 15, and revolubly mounted on the frame at the underside of the platform are a coned 65 or tapered packing roller 16 and a preferably cylindrical packing roller 17. The numeral 18 indicates a suitable axle or trunnions on the roller 16, and 19 indicates the 70 axle of the roller 17.

The rollers are approximately radially arranged relatively to the post 10 and at a suitable angle to each other, being disposed in practice from 60° to 90° apart. The tapered roller 16 is positively driven as hereinafter explained, and it is therefore disposed with the larger end outermost so that the driving of the same will cause the packer to traverse a circular path about the post 10 75 as an axis. The cylindrical roller 17 is 80 made up of separate and independent disks loose on the axle 19 so that the respective disks may travel at different peripheral speeds.

The frame elements and the general bearing members and hangers to support the rollers may be suitably constructed, there being in the example shown an angular bearing bracket 20 at the adjacent ends of the rollers and formed with a pendent hanger 90 member 21 affording a bearing for the shaft or trunnion at one end of the roller 16. Said angle plate 20 is shown as secured by an angle bracket 22, bolted as at 23 to the platform 15. To support the outer ends of the 95 respective rollers, a plate 24 is suitably secured to the platform 15 and formed at one end with a bearing member 25 for the outer end of the shaft 19, and with a suitable bearing member 26 for the outer end of the 100 roller 16. A bolt 27 may be employed connecting the hanger plate 20 and its bracket 22 with the said plate 24.

In order that the packer may revolubly and slidably engage the centering post 10, 105 and at the same time be permitted to accommodate itself to the surface irregularities of the ensilage A, I provide on the frame a bearing 28 having a vertical bore 29 to slidably receive the post 10. The said bearing 110 block is rockably secured at its outer end to a yoke or fork 31, the inner end or base of

which as best seen in Fig. 3 is swiveled, advantageously by the reduced and headed end 32 of the shaft 19.

The roller 16 is power driven and in practice any suitable motor may be employed for the purpose, there being shown conventionally an internal combustion motor 33. On the shaft 34 of the motor is a pinion 35 meshing with a pinion 36 on a short shaft 37 suitably mounted in the frame. The shaft 37 carries a pinion 38 which in turn drives a gear wheel 39 in fixed relation to the roller 16. Thus, the said roller 16 will be revolved on its axis and thereby caused to traverse a circular path which will cause the complete packer to revolve about the post 10.

The numeral 40 indicates a guard rail on the platform 15. In practice, the operator will stand on the platform 15 adjacent to the rail 40 to distribute the ensilage which, as usual, is received through a pipe, (not shown). At the same time the operator may control the motor 33.

Having thus described my invention, I claim as new, and desire to secure by Letters Patent:

1. A packer of the class described including a frame, a post to center the frame in a silo, an approximately radial packing roller carried by the frame, a bearing vertically rockable on the frame and slidably and revolubly embracing the post, and means to revolve the frame about the said post as an axis.

2. A packer of the class described including a frame, a post to center the frame in a silo, an approximately radial packing roller carried by the frame, a vertical bearing on the frame and slidably and revolubly embracing the post, a yoke in which the said bearing is rockable vertically, the said yoke having a swiveled connection with the frame, and means to cause said frame and rollers to travel about the post as an axis.

AMBROSE LAWRENCE.
